(57) **CLAIM**

The ornamental design for a folding cutter knife, as shown and described.

DESCRIPTION

FIG. 1 is a front elevational view of a folding cutter knife showing my new design;

FIG. 2 is a rear elevational view thereof;

FIG. 3 is a top plan view thereof;

FIG. 4 is a bottom plan view thereof;

FIG. 5 is a right side view thereof;

FIG. 6 is a left side view thereof;

FIG. 7 is a front elevational view thereof with the blade being partially pulled out;

FIG. 8 is a rear elevational view thereof with the blade being partially pulled out;

FIG. 9 is a top plan view thereof with the blade being partially pulled out;

FIG. 10 is a bottom plan view thereof with the blade being partially pulled out;

FIG. 11 is a right side view thereof with the blade being partially pulled out;

FIG. 12 is a left side view thereof with the blade being partially pulled out;

FIG. 13 is a front elevational view thereof with the blade being fully pulled out;

FIG. 14 is a rear elevational view thereof with the blade being fully pulled out;

FIG. 15 is a top plan view thereof with the blade being fully pulled out;

FIG. 16 is a bottom plan view thereof with the blade being fully pulled out;

FIG. 17 is a right side view thereof with the blade being fully pulled out;

FIG. 18 is a left side view thereof with the blade being fully pulled out;

FIG. 19 is a front elevational view thereof with the implement being pulled out;

FIG. 20 is a rear elevational view thereof with the implement being pulled out;

FIG. 21 is a top plan view thereof with the implement being pulled out;

FIG. 22 is a bottom plan view thereof with the implement being pulled out;

FIG. 23 is a right side view thereof with the implement being pulled out; and,

FIG. 24 is a left side view thereof with the implement being pulled out.
